CARBURETOR

Gunnar A. Wahlmark, Rockford, Ill., assignor
of one-third to Ernest J. Svenson and Charles
H. Rystrom, Rockford, Ill.

Application November 16, 1929, Serial No.
407,596. Renewed January 7, 1933

13 Claims. (Cl. 261—62)

The invention relates generally to carburetors and more particularly to carburetors adapted for use with internal combustion engines.

The primary object of the present invention is 5 to provide a new and improved carburetor wherein the necessity for high air velocities is materially reduced by providing for a downward movement of the air past the fuel discharge member and into the intake manifold so that the moving air does not have to lift the particles of fuel 10 and the tendency of the vaporized fuel to condense is substantially eliminated.

Another object is to provide a new and improved carburetor having the parts thereof arranged 15 so that the main air supply may flow through the carburetor without making sharp turns which might cause variation in the operation of the carburetor at its various adjusted positions.

20 Another object is to provide a carburetor having a fuel discharge member with a plurality of ducts therein arranged to discharge fuel into the carburetor at varying heights above the normal liquid fuel level, together with means for 25 controlling the various discharge ducts so that the ducts which discharge closest to the fuel level are utilized to supply fuel for the lower ranges of motor speeds, the control means being operable to bring the other fuel discharge ducts 30 into play so as to supply additional fuel for the higher ranges of speeds.

Another object is to provide a carburetor composed of a minimum number of parts each of 35 which is simple in form, and which may be readily assembled to provide a compact and efficient carburetor.

Another object is to provide a carburetor having a new and improved fuel discharge member embodying a fuel distributing chamber from 40 which fuel may pass into the main mixing chamber through a plurality of discharge ducts, the fuel discharge member having an air passage opening in the direction from which the main air supply comes and arranged to discharge air 45 into the distributing chamber to be mixed with the fuel and discharged therewith through the discharge ducts.

Other objects and advantages will become apparent from the following description taken in 50 connection with the accompanying drawing, in which:

Figure 1 is a vertical sectional view of a carburetor embodying the preferred form of the invention, the section being taken along the line 55 1—1 of Fig. 3.

Fig. 2 is a vertical sectional view of the carburetor taken along the line 2—2 of Fig. 3 showing the parts of the carburetor in idling position.

Fig. 3 is a plan section of the carburetor taken 60 along the line 3—3 of Fig. 2 with the cover and throttle member removed.

Fig. 4 is a sectional view taken along the line 4—4 of Fig. 1.

While the invention is susceptible of various 65 modifications and alternative constructions, I have shown in the drawing and will herein describe in detail the preferred embodiment, but it is to be understood that I do not thereby intend to limit the invention to the specific form 70 disclosed, but intend to cover all modifications and alternative constructions falling within the spirit and scope of the invention as expressed in the appended claims.

In the drawing the invention is illustrated as 75 embodied in a carburetor having a main body of box-like form provided by a casting 9 having a bottom wall 10, upstanding outer side walls 11 and an annular vertical inner wall 12 spaced from the side walls 11 to provide an intermediate 80 chamber 13. The annular wall 12 also provides a vertical passageway 14 extending through the body. A narrow bar 15 extending diametrically across the lower end of the passageway 14 supports a fuel discharge member 16 within the passageway so that air drawn through the passageway may be mixed with fuel to provide a combustible fuel mixture for an internal combustion motor. At the lower end of the passageway a 90 flange 17 (Fig. 2) is formed on the body and adapted for connection to the intake manifold (not shown) of a motor so that during operation of the motor, air will be drawn downwardly through the passageway 14 past the fuel discharge 95 member 16.

The chamber 13 surrounding the annular wall 12 serves as a fuel supply chamber and is closed at its upper end by means of a removable cover plate 18 suitably secured in position on the casting 9 and having an aperture 19 therein arranged to register with the passageway 14 so as to permit air to move downwardly therethrough. Liquid fuel is supplied to the chamber 13 through a passage 19^a (Fig. 1) in the casting, the passage being suitably connected to a supply tank (not shown). To maintain a constant fuel level within the chamber a float-operated valve 20 is mounted within the chamber. A sleeve 21 (Fig. 1) positioned in the passage 19^a slidably sup-

ports the valve 20 in vertical position and provides a valve seat therefor.

To control the valve 20 a pair of floats 22 are positioned in two adjacent corners of the chamber 13 on the opposite sides of the chamber. Each float is connected by means of an arm 23 to a horizontal rock shaft 24 mounted in the side walls 11, the arms extending through the narrow spaces on the opposite sides of the annular wall 12 and being secured to the rock shaft 24 adjacent the ends thereof. At substantially the mid-point of the rock shaft another arm 25 is secured with the end thereof engaging the upper end of the valve member 20 so that rocking movement of the shaft 24 serves to move the valve toward and away from the valve seat. Through the action of the float valve 20, the fuel is maintained at a constant level within the chamber 13, this level being indicated by a dotted line in Figs. 1 and 2.

20 Liquid fuel from within the float chamber 13 passes to the fuel discharge member 16 through a horizontal bore 26 (Fig. 1) formed in the bottom wall 10 and the radial bracket 15, the flow of fuel into the bore 26 through a port 26^a being controlled by a vertically adjustable needle valve 27 mounted in the casting 9.

In order that the fuel discharged from the member 16 may be thoroughly mixed with air to form a combustible fuel mixture, means is positioned within the passageway 14 arranged to cause air passing downwardly through the passage to suck fuel out of the discharge member and to atomize it into a readily combustible mixture which passes out the lower end of passageway 14 for transmission to the motor. In the preferred form of the invention a plurality of Venturi passages are arranged with the throats of the passages positioned so that the liquid fuel will be drawn into the passages on the expansion side of the throats. To this end a throttle sleeve 28 is supported and guided for movement coaxially with respect to the passageway 14 by means of a trunk piston 29 slidably mounted in a cylinder 30 carried on the removable cover plate 18 of the carburetor. To permit passage of air downwardly into the passageway 14 the cylinder 30 is made of a diameter substantially smaller than the passageway 14 and is secured to the plate 18 by a plurality of comparatively thin radial webs 31 which extend from the lower edge of the cylinder to the cover plate at circumferentially spaced points about the cylinder. Thus the air may move along a substantially straight path downwardly about the cylinder 30 and into the passageway 14 as indicated by the arrows in Figs. 1 and 2.

The invention contemplates the mixing of the air with the fuel in successive stages and to this end the throttle sleeve 28 is arranged so that it extends downwardly around the upper portion of the fuel discharge member 16 so as to define an inner annular passage 32 (Figs. 1 and 4) between the fuel discharge member 16 and the sleeve 28 and to define an outer annular passage 33 between the sleeve 28 and a sleeve 33^a mounted within the passageway 14. Air is supplied to the inner annular passage 32 through a plurality of apertures 34 formed in the sleeve 28 below the lower end of the cylinder 30 and in order that there may be a Venturi effect upon the air passing therethrough, the inner surface of the sleeve is formed so as to taper inwardly and downwardly from the apertures 34 to a point 35 which constitutes the throat of the Venturi passage. From this point the surface of the sleeve 28 tapers

outwardly to the lower end of the sleeve. The outer annular passage 33 is also in the form of a venturi, this being accomplished by sloping the outer surface of the sleeve 28 outwardly and downwardly from the apertures 34 to a level indicated at 36, which constitutes the throat of the venturi, and then sloping the surface inwardly and downwardly to the lower end of the sleeve.

80

The various parts of the carburetor are proportioned so that vertical movement of the throttle sleeve 28 serves to vary the size of the inner and outer annular Venturi openings 32 and 33 and to this end the inner surface of the sleeve 33^a slopes inwardly from the two ends to the level 38 intermediate the upper and lower ends of the sleeve. Thus when the throttle sleeve 28 is moved downwardly from the position shown in Fig. 1 to the position shown in Fig. 2, the outer Venturi passage 33 will be gradually closed and the outer surface of the throttle sleeve below the level 36 will be moved into abutment with the outer sleeve 33^a to limit the throttle movement. During such downward movement of the throttle sleeve 28 the size of the inner passage 32 is gradually reduced until, in the lowermost position of the throttle sleeve, as shown in Fig. 2, a comparatively small annular opening is left between the fuel discharge member 16 and the sleeve 28 so as to allow passage of sufficient air to provide an idling mixture for the motor.

90

95

100

105

In order that the fuel discharge member 16 may cooperate with the throttle sleeve 28 to change the size of the inner passage 32 during movement of the throttle sleeve, the fuel discharge member is annular in horizontal cross section and is of greatest diameter at a level 39 intermediate the top and bottom of the member and tapers gradually from the level 39 toward the top and bottom of the member. Thus a downwardly and inwardly tapering surface 40 is provided on the lower portion of the member 16 which cooperates with the outwardly and downwardly tapering inner surface of the throttle sleeve to form the expansion side of the Venturi passage 32 when the throttle sleeve 28 is in its lower or idling position (Fig. 2).

110

115

120

125

130

As the air moves through the inner passage 32 its velocity gradually increases as it approaches the throat 35 thereof, and due to the compressible nature of air, there is also a slight compression of the air and after the air has passed the throat 35 of the venturi there is a decrease in its velocity and the air gradually expands so that there is a difference in pressure between the air on the two sides of the throat of the venturi.

The present invention utilizes this difference in pressure on the two sides of the Venturi throat to control the quantity of fuel drawn from the fuel discharge member 16 into the Venturi passage 32. To this end a plurality of fuel discharge ducts 41 are formed in the member 16 at points spaced vertically and circumferentially of the fuel discharge member, all of the ducts being arranged so that their outer ends terminate in the upwardly and inwardly tapering surface of the member 16 above the level 39. The ducts 41 are preferably formed by horizontal bores extending radially into the member 16 into communication with a plurality of longitudinal slots 42 (Fig. 4) formed in the outer surface of a plug 43 which is positioned in a vertical bore 44 formed in the discharge member. The plug 43 (as shown in Fig. 1) extends downwardly into the bore 44 to a point slightly below the normal fuel level at which point a distributing chamber 45 (Fig. 1)

128

132

140

145

150

is formed between the lower end of the plug 43 and the upper end of a stem 46 which extends upwardly into the bore 44. Thus fuel from the float chamber 13 may pass through the horizontal bore 26 and upwardly through a central bore 47 in the stem 46 into the distributing chamber 45.

It will be seen that by varying the vertical distance between the ends of the plug 43 and the stem 46 the size of the distributing chamber 45 may be varied and the effective size of the discharge ducts 41 may be changed. Thus by varying the size of the distributing chamber 45 in this manner, the amount of air or fuel which may pass through the discharge ducts 41 may be controlled.

The range of movement of the throttle sleeve 28 is preferably such that the throat 35 thereof may be moved from its lower position as shown in Fig. 2 upwardly past all of the fuel discharge ducts 41 to the position shown in Fig. 1 and thus it will be seen that by adjustment of the throttle sleeve the number of ducts 41 which open into the expansion side of the Venturi passage 32 may be varied at will. The air passing through the expansion side of the venturi moves directly across the ends of the discharge ducts 41 positioned below the throat of the venturi 35 and this air has an aspirating effect which tends to draw fuel from the distributing chamber 45 through the ducts 41.

This aspirating tendency of the moving air on the expansion side of the Venturi throat 35 is augmented by providing an air passage 48 extending from the upper end of the fuel discharge member 16 downwardly through the plug 43 into the distributing chamber 45. Thus through the medium of the air passage 48 the fuel in the distributing chamber 45 is subjected to the pressure from the compression side of the Venturi passage 32 which tends to force the fuel through the ducts 41 which, at the particular time, are positioned so that their discharge ends open into the expansion side of the venturi.

It will be seen, however, that when any one of the ducts 41 has its discharge end positioned above or on the compression side of the throat 35 of the venturi 32 the pressure on the compression side of the venturi will act through the duct 41 to offset the equal pressure applied through the air passage 48 and hence the duct or ducts 41 in this position will not act as fuel discharge passages. These ducts may also supply air to the distributing chamber 45 to be mixed with the liquid fuel and discharged therewith through the ducts opening below the Venturi throat 35.

The upper end of the air passage 48 is flared outwardly as shown in Fig. 1, so that when the motor speed has been increased to its highest point, the rush of the air past the upper edge of the passage 48 will aspirate fuel upwardly through the passage. At such high speeds the velocity of the air moving through the annular Venturi passage 32 is sufficient to draw fuel through all of the ducts 41 without the aid of pressure acting through the passage 48 so that the utilization of the passage 48 for discharging fuel does not impair the efficiency of the carburetor and enables the carburetor to provide a larger quantity of fuel mixture.

The air which enters the distributing chamber 45 through the passage 48 or the ducts opening above the Venturi throat, mixes with the liquid fuel in the distributing chamber so that a mixture of air and fuel is discharged into the

inner passage 32 where it is mixed with a greater quantity of air. From the inner passage 32 the fuel mixture moves into the space between the lower tapering surface 40 of the fuel discharge member and the outer sleeve 38 to be mixed with the air which comes through the outer annular passage 33 so as to produce a properly proportional fuel mixture.

With the fuel discharge ducts 41 and the controlling throttle sleeve 28 arranged in the relation herein shown, the ducts 41 whose discharge ends are the shortest distance above the fuel level are utilized for supplying an idling mixture so that less suction is required to draw the fuel from the ducts and the carburetor may be adjusted to provide a more satisfactory idling mixture than has been heretofore possible.

This arrangement also insures a rapid motor acceleration since a comparatively small amount of suction is required to bring additional ducts 41 into play as the throttle sleeve 28 is raised.

After the fuel mixture has been formed as above described, it moves downwardly out of the passageway 14 and into the intake manifold (not shown) of the motor and since the moving air 100 with which the fuel is mixed does not have to lift particles of fuel, the tendency of the fuel to condense or settle out of the air is substantially eliminated. It will be noted that the major portion of the air passes through the carburetor along a substantially straight path so that the variable factors which result from the passage of air along a curved or angular path are avoided and uniform operation of the carburetor in all of its adjusted positions is assured.

To aid in providing a rich mixture for the starting of the motor, a tubular member 49 is positioned about the cylinder 30 in spaced relation thereto so that the air moving downwardly into the passageway 14 must move through the member 49, and a valve 50 of the butterfly type is mounted on a shaft 51 extending across the upper end of the member 49. By closing the valve 50 the suction of the motor acts directly upon the fuel discharge ducts 41 so that an unusually large quantity of fuel is drawn therefrom and a rich fuel mixture is provided.

The throttle sleeve 28 is moved up and down by means of a lever 52 mounted in the upper end of the cylinder 30 on a shaft 53 which extends transversely through the cylinder 30 and the tubular member 49, the outer end of the lever being connected to the piston 29 by means of a link 54. An arm 55 (Fig. 2) secured on the shaft 53 outside of the member 49 may be connected to a suitable foot pedal or manual actuating device (not shown). When the manual actuating device is moved at a given rate the throttle sleeve 28 will be moved upwardly at a comparatively slow rate at first since the vertical component of a given arcuate movement of the arm 52 will be small when the arm is near its vertical position. As the throttle sleeve 28 approaches its open position its rate of movement relatively to the rate of movement of the manual actuating device will of course increase materially since the lever will be approaching its horizontal position shown in Fig. 1 wherein the vertical component of a given arcuate movement of the lever will be comparatively great.

Thus the actuating mechanism provided enables the operator to control more accurately the fuel mixture and the resulting acceleration of the motor in its lower range of speeds. An adjustable stop device 56 on the shaft 53 outside

of the tubular member 49 engages an abutment on the member 49 to limit the movement of the actuating mechanism and thereby control the idling position of the throttle sleeve.

- 5 In order that the throttle sleeve 28 may be more easily and accurately controlled by the operator, means is provided for counteracting the tendency of the sliding sleeve to be moved downwardly by the action of the motor suction. This 10 means preferably includes the piston 29 and cylinder 30 which support and guide the throttle sleeve 28. A passage 57 formed in the body 12 and the wall of the cylinder 30 extends from the passage 14 to the cylinder at a point above the piston 29. The top of the cylinder is closed by a plate 15 58.

Thus the suction of the motor is applied directly through the passage 57 to the upper side of the piston 29 so that the same suction source which 20 acts downwardly on the throttle sleeve 28 also acts to move the sleeve upwardly. Thus by properly proportioning the size of the piston and cylinder 30 an equalizing force is applied to the moving parts so that the operator may more easily 25 and accurately control the movement thereof.

From the foregoing it will be apparent that the invention provides a carburetor composed of a comparatively small number of simple parts which may be readily assembled to form a carburetor which operates with unusual efficiency 30 due to the fact that the air is drawn downwardly through the carburetor and into the intake manifold so as to avoid condensation of the liquid fuel out of the fuel mixture. It will also be seen that 35 since the principal portion of the air passes through the carburetor along a substantially straight path, the carburetor will function uniformly in all of its various adjusted positions.

It will also be apparent that since the fuel 40 discharge ducts which are nearest to the liquid fuel level are brought into play in the lower range of motor speeds the carburetor will provide for a more uniform motor acceleration and will also provide a more satisfactory idling fuel mixture.

45 I claim as my invention:

1. A carburetor comprising a body having a vertical passageway therethrough with a wall shaped to form the outside of a Venturi passage, means at the bottom of said passage adapted for 50 connection with the intake manifold of a motor so that a down-draft will be produced in said passageway, fuel supply means, and fuel vaporizing and mixing means within said passageway operable by air moving downwardly through said 55 passage to produce the combustible fuel mixture and comprising a conical fuel discharge member positioned centrally in said passage and having fuel discharge ducts, means forming an inwardly inclined annular wall on said passage 60 adjacent said member and an annular throttle member of wedge shaped section movable vertically intermediate said member and wall and cooperating with the wall of said conical member to form a first Venturi passage, and cooperating 65 with the wall of said passageway to form a second Venturi passage, said annular throttle member acting to enlarge the throats of both Venturi, passages simultaneously as it is moved from its idling to its open position.

- 70 2. A carburetor comprising a hollow body having a vertical passageway with its intake at the upper end and means at the lower end of said passageway adapted for connection with the intake manifold of a motor so that a down-draft will be produced in said passageway, a fuel sup-

ply chamber adjacent to said passageway, a fuel discharge member supported in said passageway and shaped to form the inside of a venturi, said member having a plurality of discharge ducts therein each arranged to receive fuel from said chamber and terminating at different levels in said passageway above the normal fuel level in said chamber, and a control member supported from above said member and movable in said passageway to control the passage of air through said passageway and past said ducts, said control member cooperating with said fuel discharge member to form a venturi with its throat substantially on a plane with the normal fuel level when the control member is in its idling position, and being movable upwardly to simultaneously raise and enlarge the throat of the venturi and draw fuel from increasing numbers of said discharge ducts.

3. A carburetor comprising a body having a substantially vertical passageway therethrough with a wall shaped to form the outside of a venturi and means at the lower end adapted for connection with the intake manifold of a motor so that 100 a down-draft will be produced in said passageway, fuel discharge means shaped to form the inside of a venturi and providing a plurality of ducts opening into said passageway at different levels, and movable means for controlling the 105 passage of fuel through said ducts cooperating with the fuel discharge means to form a first venturi, and cooperating with the wall of said passageway to form a second venturi and operable in one position to permit passage of fuel 110 through the lower ducts only so that only a small amount of suction will be required to draw fuel into the passageway, said movable means being operable as it is moved from said position to 115 shift the throat of the first venturi and draw fuel through the successively higher ducts in addition to said lower ducts.

4. A carburetor comprising a hollow body having a substantially vertical passageway therethrough, and a chamber for containing a liquid fuel, a fuel discharge member supported centrally in said passageway, said member having a plurality of discharge ducts therein arranged to receive fuel from said chamber and terminating 125 at different levels in said passageway above the normal fuel level in said chamber, control means supported from above said member and movable in said passageway to control the flow of fuel through said ducts into said passageway and 130 including an annular member positioned between said discharge member and the wall of said passageway and movable from a lower position in which it substantially closes said passage to an upper 135 position wherein it divides said passage and directs a portion of the air past said ducts, and means at the lower end of said passageway for connecting said lower end to the intake manifold of a motor.

5. A carburetor comprising a hollow body having a substantially vertical passageway therethrough and a chamber for containing liquid fuel, a cylinder above said body positioned coaxially with respect to said passageway, said 145 cylinder being of less width than said passageway so as to permit air to traverse a substantially straight path downwardly along the sides of said cylinder into said passageway, a fuel discharge member supported in said passageway, said 150

member having a plurality of discharge ducts therein arranged to receive fuel from said chamber and terminating at different levels in said passageway above the normal fuel level in said chamber, a piston in said cylinder, control means supported from said piston and movable in said passageway to control the flow of fuel through said ducts into said passageway, and means on said body for connecting said lower end to the intake manifold of a motor.

ranged to permit passage of air downwardly therethrough, said sleeve being movable vertically along said member to vary the position of the throat of the venturi relatively to the ends of the various discharge ducts, said member also having a passage formed therein extending upwardly from said distributing chamber to the outside of said member at a point lying on the compression side of the Venturi throat, said passage having a flared upper end.

10 intake manifold of a motor.

6. A carburetor comprising a hollow body having a substantially vertical passageway and adapted at its lower end for connection with the intake manifold of a motor so that a down-draft
15 will be produced in said passageway, a float chamber adjacent to said passageway for containing liquid fuel, a fuel discharge member supported in said passageway, said member being of less diameter than said passageway so as to permit passage of air and being of circular horizontal cross-section tapering toward its upper end, said member also having a plurality of discharge ducts therein arranged to receive fuel from said chamber and opening through the upwardly tapering surface of said member at different levels in said passageway above the normal fuel level in said chamber, and an annular control member surrounding said member and cooperating therewith to form a Venturi passage
20 and movable up and down in said passageway to vary the position of the throat between the control member and the tapering surface of said discharge member and to control the flow of fuel through said ducts into said passageway.

25

30

9. A carburetor comprising a hollow body having a passageway therethrough, a fuel discharge member adjustably positioned in said passageway, said member having a plurality of ducts formed therein through which fuel may be drawn into said passageway, a movable control member in said passageway operable to govern the number of ducts through which fuel may simultaneously be drawn, said control member also being operable to govern the amount of air passing through said passageway, and a third member in said passageway arranged to determine the idling position of said control member, said third member being adjustable to permit of varying said idling position and being arranged to cooperate with said control member when said control member is moved away from its idling position to form a second air passage therebetween.

35 7. In a carburetor, the combination of a body having a substantially vertical passageway and adapted at its lower end for connection to an intake manifold of an engine so as to produce a down-draft through the passageway and a
40 chamber adapted to contain liquid fuel, a fuel discharge member in said passageway having an outer surface tapering inwardly and upwardly, said member also having a fuel distributing chamber therein communicating with said float
45 chamber and positioned below the normal fuel level in said float chamber, a plurality of fuel discharge ducts formed in said member leading from said distributing chamber to the outside of said member at different levels on said upwardly tapering surface, and a Venturi sleeve surrounding said member and movable vertically along said member to vary the position of the throat of the venturi relatively to the ends of the various discharge ducts, said member also having
50 a passage formed therein extending from said distributing chamber to the outside of said member at a point lying on the compression side of the Venturi throat.

10. A downdraft carburetor comprising, in combination, a hollow body having a substantially vertical passageway therethrough and adapted at its lower end for connection to the intake manifold of a motor, a cylinder supported on said body in the upper end of said passageway, said cylinder being of less width than said passageway so as to define an opening between the cylinder and the wall of the passageway to permit air passing through the carburetor to traverse a substantially straight path, a fuel discharge member in said passageway below said cylinder, means for supplying fuel to said discharge member, a piston in said cylinder, a manually operable control member supported by said piston operable to control the flow of fuel from said discharge member and movable upwardly to increase the motor speed so that the suction in the passageway tends to move the control member downwardly to its idling position, and means providing a passage between the upper end of said cylinder and said passageway on the suction side of said control member to substantially equalize the suction on said control member and reduce the effort necessary to raise the control member manually.

Venturi throat.

8. In a carburetor, the combination of a body having a substantially vertical passageway therethrough and a chamber adapted to contain liquid fuel, means for connecting the lower end of said passageway to the intake manifold of a motor so that a down-draft will be created in said passageway, a fuel discharge member in said passageway having an outer surface tapering inwardly and upwardly, said member also having a fuel distributing chamber therein communicating with said float chamber and positioned below the normal fuel level in said float chamber, and a plurality of fuel discharge ducts formed in said member leading from said distributing chamber to the outside of said member at different levels on said upwardly tapering surface, and a Venturi sleeve surrounding said member and ar-

75

11. A downdraft carburetor comprising, in combination, a hollow body having a substantially vertical passageway therethrough and adapted at its lower end for connection to the intake manifold of a motor, a cylinder supported on said body in said passageway, said cylinder being of less width than said passageway so as to define an opening between the cylinder and the wall of the passageway to permit air passing through the carburetor to traverse a substantially straight path, a piston in said cylinder, a fuel discharge member in said passageway, means for supplying fuel to said discharge member, a manually operable control member carried by said piston operable to control the flow of fuel from said discharge member and normally moved toward its idling position by the suction in said passage, and means providing a passage between one end of said cylinder and said passageway on the suction side of said control member substantially to equalize the suction on said control member and

reduce the effort necessary to move the control member manually to increase the motor speed.

12. A carburetor comprising a body having a vertical passageway therethrough with a wall shaped to form the outside of a Venturi passage, means at the bottom of said passage adapted for connection with the intake manifold of a motor so that a down-draft will be produced in said passageway, fuel supply means, and fuel vaporizing and mixing means within said passageway operable by air moving downwardly through said passage to produce the combustible fuel mixture and comprising fuel discharge means positioned centrally in said passage and including a member shaped to form the inside of a Venturi passage, and an annular throttle member movable vertically intermediate said fuel discharge means and said wall and cooperating with the fuel discharge means to form a first Venturi passage and cooperating with the wall of the passageway to form a second Venturi passage, said throttle member acting to enlarge the throats of both Venturi passages simultaneously as it is moved from its idling to its open position.

25

13. A carburetor comprising a body having a vertical passageway therethrough with a wall shaped to form the outside of a Venturi passage, means at the bottom of said passage adapted for connection with the intake manifold of a motor so that a down-draft will be produced in said passageway, fuel supply means, and fuel vaporizing and mixing means within said passageway operable by air moving downwardly through said passage to produce the combustible fuel mixture and comprising fuel discharge means positioned in said passage and shaped to form the inside of a Venturi passage, and an annular throttle member movable vertically intermediate said fuel discharge means and the wall of the passage and cooperating with said fuel discharge means to form a first Venturi passage through which primary air passes to mix with the fuel from the discharge means and cooperating with the wall of said passageway to form a second Venturi through which secondary air passes to mix with the primary air and fuel.

- reduce the effort necessary to move the control member manually to increase the motor speed.
12. A carburetor comprising a body having a vertical passageway therethrough with a wall shaped to form the outside of a Venturi passage, means at the bottom of said passage adapted for connection with the intake manifold of a motor so that a down-draft will be produced in said passageway, fuel supply means, and fuel vaporizing and mixing means within said passageway operable by air moving downwardly through said passage to produce the combustible fuel mixture and comprising fuel discharge means positioned centrally in said passage and including a member shaped to form the inside of a Venturi passage, and an annular throttle member movable vertically intermediate said fuel discharge means and said wall and cooperating with the fuel discharge means to form a first Venturi passage and cooperating with the wall of the passageway to form a second Venturi passage, said throttle member acting to enlarge the throats of both Venturi passages simultaneously as it is moved from its idling to its open position.
13. A carburetor comprising a body having a vertical passageway therethrough with a wall shaped to form the outside of a Venturi passage, means at the bottom of said passage adapted for connection with the intake manifold of a motor so that a down-draft will be produced in said passageway, fuel supply means, and fuel vaporizing and mixing means within said passageway operable by air moving downwardly through said passage to produce the combustible fuel mixture and comprising fuel discharge means positioned in said passage and shaped to form the inside of a Venturi passage, and an annular throttle member movable vertically intermediate said fuel discharge means and the wall of the passage and cooperating with said fuel discharge means to form a first Venturi passage through which primary air passes to mix with the fuel from the discharge means and cooperating with the wall of said passageway to form a second Venturi through which secondary air passes to mix with the primary air and fuel.

CERTIFICATE OF CORRECTION.

Patent No. 1,927,426.

September 19, 1933.

GUNNAR A. WAHLMARK.

It is hereby certified that the above numbered patent was erroneously issued to the inventor said "Wahlmark" as assignor of one-third interest to "Ernest J. Svenson and Charles H. Rystrom" whereas said patent should have been issued to the inventor said "Wahlmark" as assignee of one-third interest to Ernest J. Svenson, and one-third to Charles H. Rystrom, as individuals, as shown by the records of assignments in this office; and that the said Letters Patent should be read with this correction therein that the same may conform to the record of the case in the Patent Office.

Signed and sealed this 28th day of November, A. D. 1933.

F. M. Hopkins
